UNITED STATES PATENT OFFICE

WILLIAM H. NICKERSON, OF NEWTON, MASSACHUSETTS

MEANS FOR FORMING SHANK STIFFENERS

Application filed September 8, 1928. Serial No. 304,628.

This invention relates to means for forming from a work strip of sheet metal, a shoe shank stiffener having a predetermined longitudinal curvature, a longitudinal recess in one side, a corresponding longitudinal ridge or projection on the opposite side, and a varying width between its longitudinal edges.

The object of the invention is to provide a pair of coacting dies, having cutting edges adapted to sever a stiffener from a sheet metal work strip, and thus form the margin of the stiffener, and a molding rib carried by one of the dies and adapted to provide the stiffener with the above-mentioned recess and projection, the form of the dies being such that they impart a longitudinal curvature to the stiffener, one of the dies being a female and the other a male die.

Of the accompanying drawings forming a part of this specification,—

Figure 1 is a perspective view of the female die.

Figure 2 is a perspective view of the male die.

Figure 3 is a side view of the male die.

Figure 4 shows the female die in longitudinal section, and by dotted lines a completed stiffener discharged from the female die.

Figure 5 shows the two dies in transverse section separated from each other.

Figure 6 is a view similar to Figure 5, showing the dies coacting.

Figure 7 shows in perspective, a stiffener as formed by the dies.

Figure 8 is a plan view of a somewhat differently formed stiffener.

The same reference characters indicate the same parts in all of the figures.

The typical stiffener shown in perspective by Figure 7, in longitudinal section by Figure 4, and in transverse section by Figures 5 and 6, has a margin 12, formed by the cutting edges of the dies hereinafter described. The stiffener is longitudinally curved and has in one side a longitudinal recess, the bottom of which is designated by 13. The opposite side of the stiffener has a longitudinal ridge or projection conforming to the recess. One end of the stiffener has an inclined substan-

tially triangular portion 14, and the opposite end a flat portion 15.

The dies shown by Figures 1 to 6, are formed to produce a stiffener, formed as above described, but it will be obvious that the invention is not limited to dies adapted to produce this particular form of stiffener, and that they may be adapted to cut a margin 12 of any desired contour, impart any desired longitudinal curvature to the stiffener, and mold the stiffener within its margin to form in one side a recess, and on the opposite side a projection or ridge of any desired form. For example, the dies may be adapted to form the stiffener shown by Figure 8.

The female die shown by Figures 1 and 4, may be fixed to the bed of a press, and the male die shown by Figures 2 and 3, may be fixed to a press platen movable in a predetermined path toward and from the female die.

The body 17 of the female die is a metal block having a flat upper face and an oblong opening 18, extending through the block from side to side. The wall of the opening intersects the flat upper face, to form a continuous female cutting edge 19, surrounding the opening.

The male die 20 is an oblong metal block, formed to enter the opening 18, and having a continuous male cutting edge 21, formed by the intersection of the external surface of the block with the bottom face thereof, and adapted to cooperate with the female cutting edge 19, in severing the margin 12 of the stiffener from a work strip 22 bearing on the upper face of the female die.

The bottom face of the male die is provided with a molding rib 23, surrounded by and projecting below the male cutting edge 21. The male cutting edge 21 and the rib 23 are longitudinally curved, as shown by Figures 2 and 3, and the ends of the rib may be provided with flat portions 24 and 25, adapted to form the portions 14 and 15 of the stiffeners.

The essential form and arrangement of the parts are such that when the dies are caused to coact by the projection of the male die from the position shown by Figure 5, to that

shown by Figure 6, a stiffener is severed from the work strip 22 by the cutting edges, molded to a predetermined form by the ribbed bottom face of the male die, and forced into the opening 18 of the female die. The flat form of the top face of the female die, and the curved form of the ribbed bottom face of the male die causes the portions of the rib 23, and the portions of the male cutting edge 21 at the ends of the male die, to contact with the work strip before the intermediate portions of said rib and cutting edge so contact, so that the end portions of the stiffener are severed, molded, and forced into the opening of the female die, before the intermediate portions, the stiffener being therefore longitudinally curved while it is being otherwise formed or molded. The female die is provided with means for guiding the work strip 22 and maintaining a portion thereof in position to be acted upon by the dies, said means being preferably embodied in a top plate 27, having an opening 28, formed and arranged to receive the male die, and two spaced apart members 29, interposed between the plate 27 and the female die, the spaced apart inner edges of said members being arranged to guide the work strip.

30 Any suitable means may be provided for longitudinally feeding the work strip after each retraction of the male die. The upper portion 18^a of the female die opening is formed to frictionally engage the margins of a plurality of stiffeners forced into the opening by the male die, the frictional engagement so opposing downward movement of the engaged stiffeners that the molding of the under side of each succeeding stiffener is completed by the uppermost engaged stiffener, the recessed side of which constitutes a mold member cooperating with the molding rib 23 of the male die. The shank-delivering lower portion of the female die opening 18 is enlarged as shown by Figures 4, 5, and 6, to permit stiffeners that have been forced through the engaging portion 18^a to drop freely. In other words, the sides and ends of the opening 18 are parallel with each other in the portion 18^a, and diverge below said portion, as shown by Figures 4, 5 and 6, so that downward movement of stiffeners in the portion 18^a is frictionally opposed, the stiffeners passing downward from said portion being permitted to drop freely. A dropping stiffener is indicated by Figure 4.

The male die may be fixed to a block 30, adapted to be secured to a press platen.

60 I claim:

1. Shank stiffener forming means comprising a male die and a female die, the female die having a flat top and an opening surrounded by a continuous female cutting edge, the male die being formed to enter said

opening and having a continuous male cutting edge adapted to cooperate with the female cutting edge in severing the margin of a stiffener from a work strip, and a molding rib surrounded by and projecting below the male cutting edge, the rib and male cutting edge being longitudinally curved, the arrangement being such that when the dies coact, a stiffener is severed from a work strip, curved and molded to a predetermined form and forced into the female die opening.

2. Shank-stiffener forming means as specified by claim 1, the female die being provided with means for guiding a work strip and maintaining a portion thereof in position to be acted on by the dies.

3. Shank-stiffener forming means as specified by claim 1, the female die opening being provided with a shank-receiving upper portion formed to frictionally engage the margins of a plurality of stiffeners forced into the opening by the male die, and so oppose downward movement of the engaged stiffeners, that the molding of the under side of each succeeding stiffener is completed by the uppermost engaged stiffener, the shank-delivering lower portion of said opening being enlarged to permit completed stiffeners to drop freely.

In testimony whereof I have affixed my signature.

WILLIAM H. NICKERSON.
